CLAIM

The ornamental design for a terminal cover, as shown and described.

DESCRIPTION

FIG. 1 is a front, bottom and right side perspective view of a terminal cover, showing our new design;

FIG. 2 is a front, top and left side perspective view thereof;

FIG. 3 is a front, top and right side perspective view thereof;

FIG. 4 is a front view thereof;

FIG. 5 is a rear view thereof;

FIG. 6 is a top plan view thereof;

FIG. 7 is a bottom plan view thereof;

FIG. 8 is a left side view thereof; and,

FIG. 9 is a right side view thereof.

The broken lines in the drawings illustrate portions of the terminal cover that form no part of the claimed design.
